INVENTOR,
James A. Wilcox,
BY Howard S. Smith,
2/15 ATTORNEY

UNITED STATES PATENT OFFICE

JAMES A. WILES, OF HAMILTON, OHIO, ASSIGNOR, BY DISTRIBUTION OF COURT, TO
MABEL F. WILES, WIDOW OF SAID JAMES A. WILES, DECEASED

AUTOMATIC ASH SCREEN AND SIFTER

Application filed January 5, 1931. Serial No. 506,564.

My invention relates to new and useful improvements in ash screens and sifters for boilers, furnaces and the like.

The principal object of my invention is to provide a means for separating the partially burned coal or coke from the fine ash and its collection in a separate container so that it may be easily replaced in the combustion chamber.

10 It is another object of my invention to provide means for raising the separator screen to permit removal of the fine ash from under it and the automatic dropping of the separator screen upon closing the ash pit door.

It is an important object of my invention to provide means for attaching my device to domestic heating devices without alteration or machine operation, thus making its 20 installation simple and economical.

Other important and incidental objects of my invention will be brought out in the annexed specification and the subjoined claims.

In the accompanying drawing, Figure 1 is a sectional plan view taken through a circular heater taken below the fire bowl and upper grates. Figure 2 is a sectional view taken on the line 2—2 of Figure 1, showing the separator screen raised in full lines and 30 in the lowered position in dotted lines. Figure 3 is a sectional plan view taken through a heater having a rectangular fire box taken below the main grates. Figure 4 is a detail view of the separator screen pivot means employed in the device shown in Figure 3. And Figure 5 is a detail view of the separator screen support employed in the device shown in Figure 3.

40 The application of my invention to a heater having a circular fire pot will first be described.

Referring to the accompanying drawing, the numeral 1 designates the ash pit casting having a circular rear portion 2 whose one side is open and from which are forwardly extending parallel sides 3, 3.

The parallel sides at their open ends terminate in a casing 4 to form the enclosing 50 wall for the ash pit 5. The open end is

closed in a conventional manner by an ash door 6.

Within the rear portion 2 of the ash pit casting is a semi-circular supporting ring 7 resting upon the bottom or floor of the ash pit. The ring 7 has attached thereto two vertical bars 8—8, substantially in alignment with the sides 3—3 and at the rear of the ash pit casing.

Each bar 8 receives in a threaded hole 60 near its upper end an upwardly turned L shaped pin 9, to receive between it and the top of the bar, the downwardly turned flange or frame 10 of a perforated separator screen 11.

The screen 11 has essentially two semi-circular portions 12—13, each encircled by the frame 10 and provided with a longitudinal support 14 and a transverse support 15 between the support 14 and the frame 70 10 at the sides of the screen 11. (See Figures 1 and 2).

Adjacent the sides 3—3, and pivoted to each side frame 10 near the front of the screen, are two link bars 16—16. The lower 75 ends of the bars are also pivotedly connected to the inwardly extending ends 17—17 of a semi-circular shift ring 18 to whose center there is attached a handle member 19 extending toward the ash pit 80 door 6.

Extending upwardly from the screen 11 and at each side are two stop bars 20—20 which are so positioned that when the screen 85 is raised their upper ends will strike the grate and thus limit the upward movement of the screen.

Two pins 21—21 are received by the front flange 10 of the screen 11 so that when the 90 screen is tilted, the pins will rest on the top edge of a container 22, positioned on the ring 18 when the ash door is closed.

Now when the ash door is closed the ring 18 is forced inwardly by the contact of the 95 handle 19 and the door 6, and the links 16—16 will be inclined at an acute angle with the floor and the front of the screen 11 will drop down until the pins 21—21 rest on the edge of the container 22, as 100

indicated by the dotted lines. (See Figure 2).

The fine ash will drop through perforations 23 in the screen 11 and the partially 5 burned coal or coke in small lump form will roll down the inclined screen and into the container 22 from which they may be removed and used as fuel.

The perforations are inclined to permit 10 the use of a rake or hoe like tool without the latter becoming caught in the perforations if placed laterally.

When it is desired to remove the fine ash 15 that has fallen through the screen, the ash door is opened and the handle 19 is pulled outwardly to raise the screen until the stop bars 20—20 strike the grate above as indicated by full lines. (See Figure 2). The container is then removed and the fine ash 20 may be easily raked out.

In order to facilitate the assembly of the 25 screen halves 12—13, I have provided connector bolts 24—25 that engage the adjacent center flanges 10 of the screen halves.

The flange 10 of the screen 12 at the bolt 30 24 is provided with a slot 26 so that when the two halves are placed on the pins 9, 9, with the bolt 24 previously inserted in the frame 10 of the screen 13 with the nut placed loosely on it, the two flanges may be brought together and the nut tightened up. The forward bolt may then be easily inserted.

My device is equally adaptable to a heater 35 having a rectangular fire box and ash pit, wherein I employ a separator screen 27, similar to the screen 11 but of one piece and having a downwardly extending flange 28 to which the same tilting means previously described is attached.

In order to support the rear of the screen, 40 I employ an expandable bar 29 having hardened steel pointed ends 30, 30 that engage the side walls 31, 31 of the fire box. The bar 29 is composed of two halves 32, 33 and 45 has a reduced threaded end 34 where it passes through a center support 35 of the screen 27 and is received by a tapped hole 36 in the adjacent end of the bar 33. Each bar adjacent the support 35 is provided with 50 a radial hole 37 to receive a pin or spanner wrench. When the halves 32, 33 are unscrewed, the points 30, 30 will embed themselves in the side walls 31, 31 and provide a solid support for the screen. (See Figures 3 and 5.)

Attached to the flanges 28 immediately 55 above the bar 29 are two plates 38, 38 having a depending rear portion 39 that passes behind the bar 29 to effectively prevent its forward movement during the raising and lowering of the screen. (See Figures 3, 4 and 5.)

Having described my invention, I claim:

1. A device of the type described, including 60 a grate and an ash pit, a vertical support

in the rear portion of the ash pit, a screen pivoted at its rear portion to the vertical support beneath the grate, a longitudinally movable member in the bottom portion of the ash pit, an unburned fuel container resting upon said longitudinally movable member, and link bars pivotally connected between the front portion of the screen and the longitudinally movable member whereby, when the latter is moved inwardly, the front end of the screen will be lowered to deliver the unburned fuel into the container.

2. A device of the type described, including 65 a grate and an ash pit, a vertical support in the rear portion of the ash pit, a screen pivoted at its rear portion to the vertical support beneath the grate, a longitudinally movable member in the bottom portion of the ash pit, an unburned fuel container resting upon said longitudinally movable member, link bars pivotally connected between the front portion of the screen and the longitudinally movable member, a shift ring secured to the front portion of the longitudinally movable member, and a handle 70 on the shift ring whereby when the handle is pushed inwardly, the front end of the screen will be lowered to deliver the unburned fuel into the removable container while the fine ash drops through the screen into the ash pit.

3. A device of the type described, including 75 a grate, and an ash pit, an expandable bar secured between the rear side walls of the grate, a rectangular screen pivotally supported at its rear end upon said bar, a longitudinally movable member in the bottom portion of the ash pit, an unburned fuel container resting upon the front part of said longitudinal member, and link bars 80 pivotally connected between the front portion of the screen and the longitudinally movable member.

In witness whereof I have hereunto set 85 my hand this 3rd day of January, 1931.

JAMES A. WILES.
